(57) **CLAIM**

The ornamental design for a front door lining for automobile, as shown and described.

DESCRIPTION

FIG. 1 is a perspective view from a front and right side of a front door lining for automobile;

FIG. 2 is a perspective view from the front and left side thereof;

FIG. 3 is a front elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in the drawings illustrate portions of the front door lining for automobile that forms no part of the claimed design.
